UNITED STATES PATENT OFFICE.

WILLIAM C. MENZIES, OF SCRANTON, PENNSYLVANIA.

COAL-WASHING APPARATUS.

Application filed September 23, 1924. Serial No. 739,246.

My invention relates to apparatus for washing and separating coal or other similar substances from impurities whereby the said substances are rendered suitable for use.

5 The general object of the invention is to provide an apparatus by the employment of which the coal or other similar mineral substance, particularly the smaller sizes thereof, may be separated in a novel and efficient 10 manner at a minimum cost or expense.

It is also an object of the invention to provide an apparatus of novel construction through which a stream of water is adapted 15 to flow continuously at substantially constant pressure and to cooperate with the mechanical parts thereof to effect separation of the impurities from the coal or other similar material without the necessity of vibratory or jiggling movements of any of the said mechanical parts.

20 A further object of the invention is to provide a new and novel means whereby the coal or other similar mineral substance is separated from impurities which may be intermingled therewith by the action of a continuously flowing stream of water at substantially constant pressure and is translated continuously by the said stream and discharged therewith separate from the said 25 impurities.

Other objects and advantages of the invention will be pointed out in the detailed description thereof which follows or will be apparent from such description.

30 In order that the invention may be readily understood and its practical advantages more fully appreciated reference may be had to the accompanying drawings in which I have illustrated one convenient form of mechanical means embodying the invention. However, it will be understood that the invention is susceptible of embodiment in other forms of construction than that shown and that change in the details of construction 40 may be made within the scope of the claims without departing from the principle thereof.

45 In the drawings, Fig. 1 is a vertical, longitudinal, sectional elevation taken on the line 1—1 of Fig. 2;

Fig. 2 is a sectional plan view taken on the line 2—2 of Fig. 1;

Fig. 3 is a transverse sectional view taken on the line 3—3 of Fig. 1;

50 Fig. 4 is a transverse sectional view taken on the line 4—4 of Fig. 1; and

Fig. 5 is a horizontal sectional view taken on the line 5—5 of Fig. 1 showing a detail of construction.

Referring to the drawings:

1 designates as a whole the frame structure of the apparatus upon which various parts thereof are mounted and supported. The tank into which the mixture of coal or other combustible mineral substances, with 65 impurities intermingled therewith, is delivered comprises a rear wall 2, a front wall 3 and side walls 4 and 5. The material to be cleaned is discharged from a trough or chute 6 into the tank adjacent the rear wall 2 thereof and descends into the tank between the said wall and an adjustable baffle structure 10 of known construction. The material discharged from the trough 6 descends through the passageway between the baffle 10 and the adjacent wall of the tank, on to the imperforated forwardly inclined elevated portion 11 of a screen plate 11^a comprising a perforated relatively steeply inclined portion 12 adjoining the portion 11 which portion 12 is joined with the less inclined perforated portion 13 of the said plate. The lower edge of the baffle structure 10 is located a short distance above the forward edge of the portion 11 so that the material to 70 be treated is discharged into the portion of the tank wherein the washing is effected a considerable distance above the upper rear edge of the portion 13 of the perforated bottom. The forward edge portion of the said 75 screen plate rests upon the upper edge of a partition wall 15 located between and parallel with the rear and front walls 2 and 3 of the tank. The forward or front edge portion of the said screen plate extends 80 through an opening between the upper edge of the partition wall 15 and the lower edge of a plate 17 which extends between the opposite side walls 4 and 5 of the tank. The vertical depth of the said opening is adapted 85 to be controlled, for the purpose of controlling the rate of discharge of impurities from the portion of the tank above the screen plate, previously referred to, by means of an adjustable valve-like plate 20. The said 90 plate 20 is adjustable in its own plane by the adjusting screw 21.

95 The screen plate 11^a is located a considerable distance above the bottom of the tank. The water for causing separation of the impurities from the coal or other similar material is supplied from any suitable source to 100 105 110

a tank 25 and pumped from the latter through the apparatus. It is drawn therefrom through a pipe 26 by means of a rotary pump 27 from which the water is discharged 5 through the relatively flat flaring discharge conduit 28 and from the latter through an opening 29 in the wall 2. The means for operating the pump 27 consists, in the construction shown, of an electric motor 30. 10 Any suitable means may be employed for driving the rotor (not shown) of the said pump 27.

The water as it is discharged through the opening 29 in the lower part of the rear 15 wall 2 into the lower portion of the tank underneath the screen plate 11^a strikes the concaved side of a deflecting plate 31 which is of arcuate shape in cross section. This plate is situated a distance in front of the 20 inner side of the rear wall 2 and is inclined upwardly and rearwardly. Although not essential it is desirable that this plate be adjustably mounted. The mounting of said plate in order to render it adjustable may 25 be made in any suitable desired or preferred manner. In the construction, as illustrated, the said plate is provided at its opposite ends with flanges through which openings 32 in the form of slots are provided through 30 which fastening or retaining bolts 33 extend. By loosening these bolts the said plate may be adjusted either upwardly or downwardly so as to vary its position with respect to the opening 29 in the lower part 35 of the wall 2 through which the water is discharged into the tank. By adjusting the plate 31 upon the bolts 33 the angularity thereof with respect to a horizontal plane through the water delivery opening 29 is 40 varied. As a result of such variation the upward flow of the water toward the rear part of the portion 13 of screen plate 11^a is controlled to some extent which may be desirable in order to effect the most effective 45 results in the washing process. The lower edge portion of the plate 31 is located a relatively short distance in front of the rear wall 2 in a horizontal plane either coincident with or a short distance above or below a 50 horizontal plane within which the lower side of the water delivery opening 29 is located. Although the presence of the plate 31 is not absolutely essential to the operation of the apparatus it has been found that if it 55 be omitted the water is apt to flow upwardly with too great a force through the perforations in the forward portion of the screen plate 11^a underneath the separated impurities, such as slate, indicated at 35 and agitate the same. Such agitation might result 60 in causing a reintermingling of the impurities, including slate, with the coal from which it previously had been separated by the upward flow of the water through the 65 screen plate. The speed or force with which

the water is allowed or caused to flow upwardly through the screen plate must be such that flotation of the coal or other similar mineral substances may be effected without causing flotation or at any rate excessive 70 flotation of the impurities, such as slate, stone and the like. Flotation of the coal or other similar mineral substances may be effected without at the same time causing a like flotation of the impurities because the 75 specific gravity of the former is less than that of the latter as is well known. The impurities, including slate, bone and the like, gather upon the portions 12 and 13 of the screen plate and form a bed of greater or 80 less mobility. The upper rear edge of said bed practically terminates adjacent the point of discharge of the mixture to be treated from the passageway underneath the lower edge of the baffle 10 where it comes into contact with the upwardly flowing streams of water. The lower edge portion of the plate 11^a below the portion 13 is unperforated so that the relatively heavy impurities bank up at that point and retard or tend to retard 85 the outflow of said impurities from the compartment wherein separation has been effected into the discharge compartment. As a result of such retardation complete separation of the coal and impurities is effected. 90

The coal which has been floated by the upward flowing movement of the water is carried by the water over the upper edge of the plate 17 into the water-filled chamber between the said plate 17 and the upper 100 portion of the wall 3. The coal descends through the water in said chamber and is discharged through a restricted opening 40 onto an inclined, perforated plate 41. A portion of the water which enters said chamber is also discharged through said opening. It will be observed that the coal is submerged in water throughout its entire passage to the discharge opening 40. The perforations in the plate 41 are of a size to permit the water to pass through the same but are too small to permit of the passage therethrough of the particles of coal or other material. The latter, therefore, is discharged from the said plate and thereafter 105 may be conveyed to any point desired. The water which drains from the coal through the screen 41 falls on to a screen 42 over the top of the front portion of the tank 25.

The area of the opening 40 may be varied 110 by adjusting the valve 43. Adjustment of said valve may be effected by operating the lever 44.

A portion of the water which has effected the flotation of the coal or other material 115 being washed separates from the said material and flows forwardly over the top 45 of the front wall 3 and then laterally into a conduit or passageway 46 from which it is 120 discharged on to the screen plate 42, pre- 125

viously referred to. The purpose of the screen plate 42 is to prevent foreign matter, such as chips, etc., from passing with the water into the water supply tank 25.

5 It will be seen that the water is caused by the pump 27 to circulate through the system, the same water being used over and over again, the only loss being due to the adherence of the water to the coal or other 10 similar material and the impurities and perhaps some unavoidable leakage.

The impurities, including slate and the like, as previously stated, are discharged from the portion 13 of the screen plate underneath the lower edge of the adjustable plate 20 into the space underneath the inclined intermediate bottom 50 which extends forwardly from the lower edge portion of the plate 17 and which causes the 20 coal and a portion of the water to be discharged through the restricted opening 40, previously referred to. The said slate and other impurities of greater specific gravity than the coal or other similar mineral substance are discharged into the space between 25 the partition wall 15 and the lower portion of the front wall 3 and is removed therefrom by the flights 51 of an endless conveyor 52 supported upon the drums 53 and 54. The latter is adapted to be driven by means of a drive wheel 55 which in turn is driven by a drive belt 56. The means for driving the latter is not shown.

It will be observed that the water in the 35 chamber into which the slate and other impurities is discharged is in a quiet state and that the impurities discharged into said chamber descend therein on to the bottom 60 of the runway or trough in which the flights 51 operate.

For the purpose of removing sludge from the bottom of the tank and for cleansing the same I have provided openings 61 and 62 which are controlled by valves 63 and 64 which are adapted to be actuated through the medium of the levers 65 and 66 and the connecting rods 67 and 68.

For the purpose of cleaning the tank 25 or for any other purpose the water may be withdrawn or discharged therefrom through the valve controlled pipe 69.

It will be seen that by my invention I am 55 enabled to subject the coal or other similar mineral substances with the impurities intermingled therewith to the action of a stream of water which flows continuously and with a substantially constant pressure, the force of the flow being sufficient to effect lateral movement and discharge of the 60 impurities, such as slate, stone and the like of greater specific gravity. The said coal is carried forward by and with the forwardly flowing stream of water and is controlled by the latter until its final discharge 65 from the tank.

It will also be seen that by my invention I have provided means whereby the water which is delivered into the tank is divided into two streams. The stream to the left of the plate 31 flows upwardly with greater 70 force than does the other of said streams and may be regarded as effecting primary separation of the coal or other similar mineral substances from the impurities. The other of said streams which flows upwardly 75 through the forward portion of the screen plate 11^a strikes the slate and other impurities with sufficient force to effect a completion of the separation but without sufficient force to cause a reintermingling of the impurities with the previously separated coal or other similar material.

80 It has been found in actual practice by the employment of my invention a substantial reduction in cost of operation is effected, and also that a more complete separation of the coal from impurities is effected than heretofore has been practicable, as far as I am aware.

Having thus described my invention what 90 I claim and desire to secure by Letters Patent is:—

1. Apparatus for washing coal and other like substance, comprising a tank having a 95 perforated bottom inclined from the rear toward the front thereof, said bottom including an imperforate elevated portion at its rear edge, a baffle structure located in adjacent relation to the rear wall of said tank and having its lower edge terminated a short 100 distance above the forward edge of the elevated imperforate portion of said bottom whereby a passageway is formed through which a mixture of coal and impurities is 105 adapted to pass from the space between the said baffle structure and the said rear wall, a compartment in front of said baffle structure the front wall of which is of a height substantially less than the walls of the tank structure, means for discharging water 110 through the perforated portion of the said bottom and upwardly through the last mentioned compartment, a passageway underneath the said front wall through which the heavier portion of the mixture is adapted 115 to be discharged, the said bottom underneath and forwardly of said passageway being imperforate, and means forming a compartment forwardly of the first named compartment, said compartment having a 120 restricted discharge opening whereby flow of water and the lighter portion of the said mixture is restricted, substantially as described.

2. Apparatus for washing coal, comprising 125 a tank having a transversely extending intermediate wall for dividing the said tank into rear and front compartments, a bottom for the rear compartment, said bottom comprising an intermediate perforated portion,

said portion comprising two parts which are angularly related to each other, the inclination of the said bottom being toward the front of the said apparatus, and the said bottom also comprising an imperforate front edge portion, and the rear portion of the said bottom being elevated a substantial distance above the forward portion thereof, a baffle structure extending transversely of the 10 tank and located adjacent the rear wall thereof, said baffle structure being inclined rearwardly and the lower edge thereof terminating a short distance above the forward edge of the elevated portion of the 15 said bottom to form a passageway to permit the passage of coal from the space between said baffle structure and the rear wall into the washing compartment formed between said baffle structure and the said intermediate wall, means for supplying water to the 20 portion of the tank underneath the said bottom, said water flowing upwardly through the perforated portions of the said bottom and operating to separate the coal of less 25 specific gravity from the impurities of greater specific gravity, the said water overflowing the upper edge of the said intermediate wall and carrying therewith the coal of less specific gravity, and the said 30 coal being delivered into a compartment in front of said intermediate wall, the forward wall of said last mentioned compartment being provided with an opening, and means for restricting said opening to control the 35 outflow of water and coal therefrom, substantially as described.

3. Apparatus for washing coal to remove impurities therefrom, the coal being of less specific gravity than the said impurities, 40 said apparatus comprising a tank having front and rear walls and an intermediate transversely extending wall for dividing the

said tank into rear and front compartments, a bottom for closing the rear compartment, 45 said bottom having intermediate perforated portions and rear and front imperforate portions, the rear imperforate portion occupying a position a substantial distance above that of the front edge portion of the said bottom, the front edge portion of the 50 said bottom extending underneath the lower edge of the said intermediate transversely extending wall and being located a distance therefrom to form a passageway for the discharge of the impurities which may be 55 separated from the coal, a baffle structure extending transversely of the said tank and being located adjacent the rear wall thereof, the lower edge of said baffle structure terminating a distance above the front edge 60 of the elevated imperforate portion of the said bottom to form a passageway from the space between the said baffle structure and the said rear wall into the portion of the said rear compartment above the perforated 65 portions of the said bottom, a downwardly inclined plate extending from the said intermediate wall to the said front wall to divide the compartment in front of said intermediate wall into upper and lower portions, and the front wall of said tank being provided with a discharge opening, means for restricting said opening, means for supplying water under pressure to the rear compartment underneath the said bottom, 70 the said water flowing upwardly through the perforations through the said bottom into the mixture of coal and impurities and operating to effect separation thereof, substantially as described.

In testimony that I claim the foregoing as my invention, I have hereunto signed my name this 18th day of September 1924.

WILLIAM C. MENZIES.
